UNITED STATES PATENT OFFICE.

OSCAR L. OWEN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

SPOOLING-MACHINE.

1,189,285.

Specification of Letters Patent.

Patented July 4, 1916.

Application filed October 20, 1915. Serial No. 56,963.

To all whom it may concern:

Be it known that I, OSCAR L. OWEN, a citizen of the United States, and a resident of Whitinsville, county of Worcester, State 5 of Massachusetts, have invented an Improvement in Spooling-Machines, of which the following description, in connection with the accompanying drawings, is a specification, like characters on the drawings representing like parts.

This invention relates to spooling machines of the type wherein a plurality of thread guides are mounted on a horizontal support or traverse rod supported by vertical lifting rods which are reciprocated by a suitable traversing motion whereby the guides lay the threads upon the spools. In a machine of this construction it is frequently necessary to make adjustments in 10 the height of the traverse rod so that the guides contained thereon will lay the yarn on spools properly. To make this adjustment to a nicety in the present construction of spoolers requires considerable skill and labor on the part of the operative and also 15 there is a loss in the productive capacity of the machine as it is necessary to stop it while the adjustments are being made.

The object of my invention is to provide 20 simple and inexpensive means whereby the above mentioned defects are eliminated.

The novel feature of my invention will be 25 fully described in the subjoined specification and particularly pointed out in the following claim.

Figure 1, in transverse section taken 30 within one of the end frames, represents a spooling machine with my invention embodied therein. Fig. 2, is a side view showing the traverse cam, the oscillating shaft, the lifting rods and the guide bar. Fig. 3, 35 is an enlarged detail, partly broken out, showing my improved means for adjusting the level of the guide rod.

The end frames 1, middle supports 2, both 40 of suitable design to support the operative parts, the series of spool receiving spindles 3 provided with whirls 4, the driving cylin-

der 5 connected with the spindle whirls by bands 6, the bobbin holders 7, the traverse 50 rod 8 supporting the thread guides 9, the lifting rods 10 connected by links 11 and studs 12 to the lifting arm 13 on the rock-shaft 14, the oscillating arm 15 actuated by the pinion 16 on traverse motion shaft 17, 55 the actuating traverse cam 18 and spool boxes 23 may be and are all of well known construction.

In a spooling machine as usually constructed the traverse rod 8 is held in fixed 60 brackets fastened to the top of the lifting rods. With this construction when the operative finds it necessary to alter the level of the traverse rod, the lifting rod is adjusted up or down as required by changing its position in the stud holding collar 12 adjustably held on the lifting rod by the set screw 19. To accomplish this the machine must be stopped and the bobbin boxes removed from the machine in order to give the operative 65 access to the holding collar set screw 19. By the use of my invention the traverse rod 8 is supported at each end by movable brackets 20 mounted on top of the lifting rods. Each bracket is provided with means 70 for altering its relative position with the top of the lifting rod, preferably by an adjusting screw 21 threaded into the body of the bracket and impinging on the top of the lifting rod. The adjustment of the traverse 75 rod is effected by raising or lowering the brackets with relation to the top of the lifting rods by the turning of the adjusting screw. After the proper position of the rod has been attained the bracket is securely 80 fixed to the lifting rod by any suitable means, such for instance, the set screw 22. Owing to the open position of the adjusting screw with relation to adjacent parts of the machine, the adjustment can be readily 85 effected without stopping the machine.

What is claimed as new is:

In a spooling machine, a series of rotatable spool carriers, thread guides, a traverse rod on which they are mounted, 90 brackets holding the traverse rod and sup-

ported by vertically reciprocating members which effect the traversing of the thread guides, said brackets being provided with a vertical adjusting screw whereby the distance of the thread guide from the top of the reciprocating member is varied.

In testimony whereof, I have signed this

specification in the presence of two witnesses.

OSCAR L. OWEN.

Witnesses:

CHARLES A. ALLEN,
JOHN F. McGINNIS.
